Specification for Design.

Patented May 4, 1920.

Application filed January 18, 1917. Serial No. 143,179. Term of patent 3½ years.

To all whom it may concern:

Be it known that I, EMMETT M. HOWARD, a citizen of the United States, residing at Merchantville, in the county of Camden, State of New Jersey, have invented a new, original, and ornamental Design for Phonographic-Disk-Record Cabinets, of which the following is a specification, reference being had to the accompanying drawing, forming part thereof.

The figure is a perspective view of a phonographic disk record cabinet, showing my new design.

I claim:

The ornamental design for a phonographic disk record cabinet, as shown.

EMMETT M. HOWARD.
